UNITED STATES PATENT OFFICE.

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

COUNTING AND INDICATING MECHANISM.

Application filed January 2, 1923. Serial No. 610,357.

The present invention relates to indicators, and more specifically to marking devices for sheets, preferably sheets of paper that are fed successively to a ruling or other machine, and which may be taken from a roll or strip which is cut into individual sheets prior to being fed to the apparatus that is to rule or otherwise operate on them.

In the accompanying drawings:

10 Figure 1 is a plan view of the preferred embodiment of the invention.

Figure 2 is a side elevation of the same,

15 Figure 3 is a side elevation of the marking implement.

Figure 4 is a longitudinal sectional view therethrough,

Figure 5 is a detail sectional view substantially on the line 5—5 of Figure 1,

20 Figure 6 is a detail sectional view showing the overthrow preventing means for the ratchet wheel.

Inasmuch as the sheet-moving and severing mechanism per se forms no part of the present invention, only sufficient portions 25 thereof are herein illustrated to make clear the indicating or marking means. A portion of the frame, of a well-known type of sheet severing apparatus, is shown at 7, and includes a shaft 8, on which the sheet severing 30 drum may be mounted. Rollers 9 are illustrated, over which the severed sheets pass in their movement toward the ruling machine.

35 Mounted in the frame 7, above the rollers 9, is a rock shaft 10 that carries the indicating or marking implement. As illustrated more particularly in Figures 1, 3 and 4, this implement consists of an ink reservoir 11, from which projects spaced arms 12. Journaled on the shaft 10, is an ink supply roller 13, that extends into the reservoir 11 and consequently into the ink placed therein. A 40 scraper 14 operates against the rear side of the roller, while the front side is engaged by a yielding band 15 carried by a roller 16 that is carried by a shaft 17 journaled in the side arms 12. This band 15 constitutes a means for transferring ink from the roller 13 to a marking wheel 18 journaled between the ends of the arms 12. The roller 18 has spaced rim portions 19 that engage corresponding rim portions 20 on the roller 13.

45 Inasmuch as the font or reservoir 11 is fixed to the rock shaft 10 by set screws 21, it will 50 be evident that this marking implement will swing whenever the rock shaft is operated. 55

One end of the shaft 10 projects beyond the side of the frame 7 and has adjustably fixed thereto a depending crank arm 22. The movement of this crank arm in one direction is stopped by a screw 23 adjustably 60 mounted in a post 24 carried by the side frame, and when the arm 22 is abutted against said screw 23, as illustrated in Figure 2, the marking roller 18 is in its elevated position and out of contact with sheets passing over the rollers 9.

Journalized on the side of the frame is a sprocket wheel 25, on which is removably hung an endless sprocket chain 26. This chain is provided with one or more lugs 27, 70 and the free end of the arm 22 is so positioned with respect to the lug 27 that as the portion of the chain 26 carrying said lug passes around the wheel 25, said lug will engage said free end of the crank arm 75 and swing the arm, thereby depressing the inking roller 18 into engagement with the sheet passing thereunder. The sprocket wheel and therefore the chain are given a step-by-step movement. To this end there 80 is fixed to the sprocket wheel a ratchet wheel 28, and an arm 29 journaled concentrically with said wheel is provided with a pawl 30 adapted to operate on the teeth of said ratchet wheel. The pawl carrying arm 85 29 is swung by a pitman 31 connected thereto at one end, and having its other end in the form of a ring 32 surrounding an eccentric 33 fixed to the shaft 8. This eccentric is adjustable upon the shaft, being held by a set screw 39 that is available through a slot 40 formed in the ring 32, as illustrated in Figure 5.

In order to prevent the overthrow of the ratchet wheel 28 and sprocket wheel 25, the former is provided in its rear side with a series of depressions 41 adapted to be engaged by balls 42 located in sockets 43 of post 44 projecting from the frame. The balls 42 are yieldingly pressed against the rear face of the sprocket wheel 28 by springs 45. Two of these posts 44 are illustrated in Figure 1, though it will be evident that one or more may be employed. The throw of the eccentric 33 is sufficient to cause 100 the pawl 30 to pass, at least two of the teeth, 105

of the ratchet wheel 28 on the rearward movement of said pawl, but means are provided, whereby the pawl may be held out of engagement with one of the two. This means, preferably, is in the form of a dog 46 detachably pivoted, as shown at 47 on the side of the frame, and held against the periphery of the ratchet wheel by a spring 48.

In connection with the operating means for the marker, an alarm or other electrically operated indicating device may be employed. As shown in Figure 2, an electric circuit closer is provided, including a spring post 49 mounted on the side frame, and having a head 50 that carries a contact element 51.

The coacting closure member consists of a spring 52 having a head 53, and this head is provided with a contact element 54 movable into and out of engagement with the element 51. The parts are normally spaced, as shown in Figure 2, but the spring 52, being in the path of the arm 22, when said arm is swung, it will strike the spring 52 and cause the contact element 54 to engage the contact element 51, thereby closing the circuit and sounding an alarm or operating any other suitable electric device.

The operation of the apparatus is substantially as follows. Assuming that the sheets are being cut and are passing successively over the rollers 9, the length of the chain 26 is such that when a predetermined number of sheets have passed, the projection 27 will come into contact with the arm 22, swinging said arm and depressing the marking implement into contact with a predetermined sheet. Assuming that the chain is of a sufficient length to cause the projection to engage the arm 22, upon the passage of every twenty-fifth sheet when the pawl 30 is permitted to engage every second tooth of the ratchet wheel, if every twenty-fifth sheet is to be marked, the dog 46 is detached by removing the pivot 47. The desired counting is thereby obtained. If every fiftieth sheet is to be marked, it is only necessary to place the dog in its active position, as shown in Figure 1. The throw of the pawl 30 remains the same, but it will be evident that such pawl will be held out of engagement with the second of each two teeth and as it will only engage one tooth, the amount of movement of the chain will be reduced by half. Obviously chains of various lengths may be provided and substituted one for the other. These chains may have any desired number of projections.

From the foregoing, it is thought that the construction, operation and many advantages of the herein described invention will be apparent to those skilled in the art, without further description, and it will be understood that various changes in the size, shape, proportion and minor details of construction may be resorted to without departing from

the spirit of sacrificing any of the advantages of the invention.

Having thus fully described my invention, what I claim as new, and desire to secure by Letters Patent, is:—

1. Article counting mechanism, comprising a movable indicating device, and means for operating it, including an endless flexible belt, means for giving a step-by-step movement to the belt, means for varying the amount of each step movement of the belt, an actuating element carried by the belt and an actuated element located in the path of the actuating element and connected to the indicating device. 75

2. In article counting mechanism, the combination with a movable indicator, of means for periodically moving it, including a wheel having ratchet teeth, a pawl that has a back and forth movement and engages the teeth when moving in one direction to rotate the wheel, means for moving the pawl past a plurality of teeth, and a dog having a mounting adjacent the periphery of the wheel for holding said pawl out of engagement with certain of said teeth and permitting its engagement with others. 90

3. In article counting mechanism, the combination with a movable indicator, of means for periodically moving it including 95 a wheel having ratchet teeth, a pawl that has a back and forth movement and engages the teeth when moving in one direction to rotate the wheel, means for moving the pawl past a plurality of teeth, and a dog pivotally mounted adjacent to the periphery of the wheel and having one end riding on the ratchet teeth and removably interposed between the pawl and certain of the ratchet teeth overrun by the latter. 105

4. In article counting mechanism, the combination with a rock shaft, of a swinging marker thereon, a crank arm on the rock shaft, associated sprocket and ratchet wheels, a pawl operating on the latter, means for holding the pawl out of coaction with the ratchet wheel during a portion of its stroke, an endless sprocket chain on the sprocket wheel, and a projection on the chain that engages the arm to actuate it when said projection passes around the wheel. 110 115

5. In article counting mechanism, the combination with a movable indicator, of an operating element having a predetermined path of movement, a circuit closer involving a movable contact element, and a device interposed between the contact element and operating element and separated from both, said device being in the path of the operating element and actuated thereby for moving the indicator, said movable contact element being in the path of the device and actuated thereby when the latter is moved. 120

6. In article counting mechanism, the combination with a movable indicator, of an 130

endless belt element having an actuating projection, means for moving the belt element, a circuit closer including a movable contact element, and a swinging arm connected to the indicator for operating it, said arm being interposed between the belt element and the contact element, and being moved by the projection to move the indicator and to operate said contact element.

7. In article counting mechanism, the combination with a rock shaft, of a marking device comprising a reservoir mounted on the

rock shaft and through which the rock shaft passes, a roller mounted on the rock shaft in the reservoir, a marking implement carried by the reservoir and having connections with the roller, an arm fixed to the rock shaft, a rotatable device having a projection that engages the arm, and means for rotating the device.

In testimony whereof, I affix my signature.

ALBERT BROADMEYER.
